COMBINED CANNED OIL DISPLAY AND CAN DRAINING CABINET

Harvey J. Smith, Greensboro, N. C., assignor to Modern Metal Products Company, Greensboro, N. C., a corporation of North Carolina

Application July 15, 1953, Serial No. 25,964

Term of patent 14 years

(Cl. D52—2)

Figure 1 is an end view in elevation of a combined canned oil display and can draining cabinet, with the display panels closed, showing my new design.

The dominant features of the design reside in the solid line portion.

I claim:

The ornamental design for a combined canned oil display and can draining cabinet, as shown and described.
